UNITED STATES PATENT OFFICE.

FLETCHER THORINGTON, OF BIRMINGHAM, ALABAMA.

MEANS FOR THE RADIO-TRANSLATION OF PHONOGRAPHICALLY-RECORDED SOUND WAVES.

Application filed December 30, 1927. Serial No. 243,611.

This invention relates to an improved apparatus for reproducing sound waves recorded on a phonographic record through the medium of a radio receiving and amplifying circuit, and more particularly to an improvement in the unit of such an apparatus which is known in the art as a "pick-up".

Heretofore pick-up units have been of either of two types, namely the capacity type and the magnetic type, but it has been found that each of these types of pick-ups has deficiencies, peculiar to the particular type of pick-up, which it is the primary object of the present invention to overcome.

15 Pick-ups of the capacity type present the disadvantage that, while the low frequencies are reproduced with remarkable trueness as to tone, the high frequency waves are inadequately amplified, and, on the other hand, 20 in the use of a pick-up of the magnetic type, the high frequencies are reproduced with a remarkable trueness of tone, but the low frequencies are not reproduced with the same effect as where a pick-up of the capacity type 25 is employed. Inasmuch as a faithful reproduction of tones representative of both high and low frequencies, is essential, if the reproduction is, on the whole, to be true to the recorded tones, the present invention contemplates the provision of a pick-up unit 30 embodying a combination of the principles of both the capacity and magnetic types of pick-ups. Therefore the present invention 35 contemplates the provision of means whereby recorded sound waves may be reproduced with a degree of accuracy which is not obtainable by the employment of pick-up units 40 of the types referred to above.

While the accompanying drawings and the 45 description which is to follow, constitute a disclosure of the preferred embodiment of the invention, it will be understood that various changes may be made within the scope of what is claimed.

45 In the accompanying drawings:

Figure 1 is a view in front elevation of the pick-up unit embodying the invention, the casing of the unit being shown in vertical section;

50 Figure 2 is a vertical transverse sectional view through the unit;

Figure 3 is a horizontal sectional view taken substantially on the line 3-3 of Figure 2 looking in the direction indicated by 55 the arrows;

Figure 4 is a view in side elevation of the unit, the right hand side of the casing shown in Figures 1 and 2 being removed;

Figure 5 is a similar view of the unit, the opposite side of the casing being removed 60 and parts which are immediately connected thereto being shown in section;

Figure 6 is a horizontal sectional view taken substantially on the line 6-6 of Figure 4 looking in the direction indicated by 65 the arrows;

Figure 7 is a detail vertical transverse sectional view through a portion of the unit;

Figure 8 is a similar view through another portion of the unit;

Figure 9 is a diagrammatic view illustrating a rectifying and amplifying circuit in which the unit may be employed.

The parts comprising the pick-up embodying the invention are housed within a casing 75 which is indicated in general by the numeral 1 and which is preferably of aluminum or other non-magnetic metal and likewise preferably formed in two sections indicated by the numerals 2 and 3, one of these sections, as for 80 example the section 2, being provided upon its outer face, with a socket member 4 adapting the casing to be mounted upon the tone arm of a phonograph. The casing sections may be held in assembled relation by any appropriate means such for example as cross rods 5, and, for a purpose to be presently explained, a supporting bracket 6 is either integrally connected or is secured at its lower end 85 to the inner side of one section of the casing, 90 as for example the said section 2, and at a point suitably spaced above the open lower end of the casing and extends upwardly substantially parallel to the said casing section and is provided at its upper end with an inwardly directed arm indicated by the numeral 7, this supporting bracket being likewise 95 of aluminum, in the preferred embodiment of the invention.

As before stated, the present invention contemplates the utilization of the principles involved in both the magnetic and capacity types of pick-ups, and as illustrated in the drawings a permanent horse shoe magnet 8 is supported within the casing 1, preferably 100 by the cross rods 5, which are of non-magnetic metal or other material suitable for the purpose, and the arms of the magnet 8 support pole pieces which are indicated by the numeral 9 and which are preferably secured at 105 110

their relatively remote ends to the relatively opposite sides of the respective arms 8 of the magnet and extend laterally inwardly from the respective arms in parallel relation to each other and are preferably provided with inward extensions indicated by the numeral 10, the opposing sides of the pole pieces, between the extension of each pole piece being recessed as at 11 to accommodate a coil 12 the 10 terminals of the winding of which are connected to suitable binding posts 13 suitably mounted upon the wall of the casing section 2, the pole pieces 10 and coil 12 being supported in symmetrically arranged positions with respect to the lower ends of the arms of the magnet 8. The electro-magnet, of which the coil 12 constitutes the field or winding, has, as its armature, a soft iron plate 14 which is embedded in the relatively narrow downward extension 15 of an aluminum plate 16 which is preferably of the rectangular form shown most clearly in Figure 4 of the drawings and which constitutes one plate of a condenser which will presently be more specifically described, and by reference to Figures 2, 4 and 6 of the drawings it will be observed that the said extension 15 of the plate 16 extends downwardly through the core of the coil 12 in concentric relation thereto with the 20 armature 14 located intermediate and opposite the extensions 10 of the pole pieces 9 of the permanent horseshoe magnet 8. The aluminum condenser plate 16 is provided at its upper edge with a short vertical extension 25 17 from the upper end of which projects a stud 18 having a substantially spherical head 19 which is disposed within a correspondingly formed socket 20 in a block 21 of rubber, the opposite sides of this block being disposed in recesses 22 formed in the two members 23 of a clamp, and the neck 18 depending between the opposing edges of the bottom walls of the recesses 22 as clearly shown in Figure 7, so as to provide for the necessary 30 40 45 vibratory movement of the plate 16 under conditions which will presently be explained. The clamping members 23 are adapted to be adjusted and held assembled by means of an adjusting screw 23' as best shown in Figure 50 7. The two clamp members 23 are supported by depending branch leaves 24 of the leaf spring 25 which is anchored at its upper end in a socket 26 provided in the bracket arm 7, a set screw 27 being threaded into the end 55 of the arm and bearing at its inner end against the said spring so as to support the spring and in turn provide for suspension of the clamp comprising the members 23, in position to suitably suspend the condenser plate 60 65 16. In order that the clamp may be adjusted so as to provide for accurate positioning of the condenser plate 16 with respect to the fixed plate of the condenser unit of which it constitutes the movable plate, and likewise to 65 provide for accurate centering of the arma-

ture 14 in the air gap between the extensions 10 of the pole pieces 9 of the magnet 8, an adjusting screw 28 is fitted through an opening 29 in the bracket member 6 and threaded into a socket 30 formed in the clamping member 70 23 which is next adjacent thereto. The adjusting screw 28 is arranged with its head in engagement with the outer side of the bracket 6, and the shank of the screw extends through a spacing and backing member 31 75 which is of rubber and which is interposed between the said one of the clamping members 23 and the said bracket 6.

The fixed plate of the condenser unit is indicated by the numeral 32 and is preferably 80 of brass and is mounted upon a supporting and backing plate 33 which is preferably of fiber, this plate being mounted by screws 34, upon arms 35 which extend laterally from the bracket 6. A conductor wire 36 is electrically connected with the fixed condenser plate 32 to a binding post 37 upon the wall of the casing section 2, a binding post 38 being also arranged upon the said wall of the casing section 2, and a conductor wire 39 being connected with this post and with the movable condenser plate 16.

In order that the extension 15 of the condenser plate 16 may be properly centered and yieldably maintained in position directly axially of the core of the electromagnet 12 and with the armature 14 located midway of the air gap between the pole piece extensions 10, a collar 40 of insulating material is arranged upon the said extension 15 immediately below 100 the said electromagnet 12, and a second collar 41 is disposed within a groove 42 formed circumferentially in the collar 40, and strands of resilient wire 43 are extended from the said collar 41, in opposite directions, and are provided at intermediate points with coils 44 to increase their resiliency, and are anchored at their ends as at 45 to the wall of the casing section 2.

The said extension 15 of the condenser 110 plate 16 is provided with a socket 46 in its lower end into which may be removably fitted the shank of a stylus 47 of the ordinary type which is to travel in the record groove of the phonograph record which is to be reproduced. 115 the stylus being held in place by the usual set screw indicated by the numeral 48.

A typical radio receiving circuit in which the pick-up embodying the invention may be employed, is illustrated diagrammatically in 120 Figure 9 of the drawings, and in this figure the numeral 49 indicates a coil which is arranged in inductive relation to the primary winding 50 of an inductance 50', the secondary winding of which is indicated by the numeral 51. A wire 53 is led from the fixed plate 32 of the capacity unit of the pick-up to one terminal of the coil 49, and a wire 54 is led from the other terminal of this coil to one terminal of the primary winding 55 of 130

an untuned radio-frequency transformer indicated by the numeral 56, a conductor wire 57 being led from the other terminal of the primary 55 of said coil to the movable plate 16 of the said capacity unit. A conductor wire 58 is led from one terminal of the primary 50 of the inductance 50' to the negative filament leads of the oscillator and detector tubes of the receiving apparatus, which tubes 10 are indicated respectively by the numerals 59 and 60. The other terminal of the primary 50 of the inductance 50' is placed in the circuit, by a wire 61, with the grid 62 of the tube 59, and one terminal of the secondary 51 of 15 the inductance 50' is in circuit with the plate of the tube 59 through a conductor wire 63, the other terminal of the secondary 51 being connected by a wire 64 to the primary 65 of an audio-frequency transformer 66 and to the 20 positive terminal of the B-battery input as shown in Figure 9. As illustrated in the said figure, a fixed condenser 67 is shunted across the wires 58 and 61 leading from the terminals of the primary 50 of the inductance 50'. 25 The secondary of the untuned radio-frequency transformer 56, indicated by the numeral 68, has one terminal connected by a wire 69 with the negative terminal of the C-battery employed in connection with the apparatus, which battery is of a strength to supply sufficient -C voltage to cause the tube 60 to operate on the lower bend of its characteristic curve, and a conductor wire 70 leads, 30 from the other terminal of the secondary 68 to the grid 71 of the tube 60, and a variable resistance 72 is in shunt with the wires 69 and 70 and serves as a means whereby the output of the circuit in which the capacity unit of 35 the pick-up, comprising the fixed and movable condenser plates 32 and 16 respectively, may be controlled.

A conductor wire 73 is connected with one of the binding posts 13 and consequently electrically connected with one terminal of the 40 electromagnetic coil 12, and leads to the other terminal of the primary 65 of the audio-frequency transformer 66, and a conductor wire 74 is connected to the binding post for the other terminal of the coil 12 and to the plate 50 of the tube 60, a variable resistance 75 being placed in shunt with the conductor wires 73 and 74 so as to provide means for controlling the output of the circuit in which the electromagnetic unit of the pick-up is located. A 55 pass condenser 74' is in shunt with the conductor wire 74 and the positive side of the B-battery input.

From the foregoing description of the pick-up it will be evident that the member which 60 comprises the movable plate 16 of the condenser constituting the capacity unit of the pick-up and the support for the armature 14 of the electromagnet 12 constituting the electromagnetic unit of the pick-up, is supported 65 for vibratory movement by the resilient ele-

ments 24, the clamp comprising the members 23, and the bushing 21 which is, as previously stated, of soft rubber, so that, as the groove of the phonographic record travels past the stylus 47, the said member comprising the 70 movable condenser plate and armature support is laterally vibrated and the amplitude of the vibrations is varied in consonance with the undulations in the lateral walls of the record groove, it being understood that this 75 vibratory movement of the said member is sufficiently yieldably resisted by the bushing 21, to avoid any undue amplification of the vibration.

By reference to Figure 9 it will be evident 80 that, in the vibration of the member which embodies the movable plate of the capacity unit of the pick-up, the amount of radio-frequency current flowing in the primary 85 of the untuned radio-frequency transformer 56, will be governed by the capacity of the fixed and movable plates of the condenser comprising the capacity unit, and inasmuch as vibration of the said member results in a consonant variation in the spacing of the 90 movable plate 16 of the condenser with respect to the fixed plate 32 thereof, the variations in current flow in the primary 55 will be in consonance with the vibrations produced by variations in the contour of the undulations in the record groove. It will be evident, at this point, that the vibratory member of the pick-up is capable of a freedom of movement which is not obtainable 95 in the case of the diaphragm of the reproducer of a phonograph, and, inasmuch as this member, in the instance of the present invention, is of aluminum and therefore exceptionally light in weight, and no appreciable impediment is offered to its vibratory 100 movement due to the action of the undulatory side walls of the record groove upon the stylus, the member will respond to all of the delicate overtones as well as to the fundamental tones of the composition impressed 110 in the record, and in this manner a faithful reproduction of the low frequencies of the musical scale is obtained. It will also be evident by reference to Figure 9 that the vibration of the vibratory member will effect a 115 variation in the position of the armature 14 between the extensions of the pole pieces of the magnet and that, therefore, consonant variations in the magnetic flux which are thus produced, will cause corresponding variations in voltage in the lead 74 between the electromagnet 12 and the plate of the tube 60 and these voltage variations will effect an 120 exceptionally faithful reproduction of the high frequencies of the recorded composition. As a consequence, due to the faithful reproduction of the higher frequencies through the medium of the magnetic unit of the pick-up, and the correspondingly faithful reproduction of the lower frequencies through the 125 130

- medium of the capacity unit of the pick-up, both units being substantially equally efficient in the reproduction of the intermediate frequencies, the combination of these units in the manner illustrated and described provides for the more faithful reproduction of all of the frequencies of a musical composition or other recorded sound waves, than is possible by the employment of these units alone.

Having thus described the invention, what I claim is:

1. Means for translating phonographically recorded sound waves into audible sound waves through the medium of an oscillating radio-receiving circuit, which circuit includes an inductance coil and a radio-frequency coil, an audio-frequency transformer, and tubes in circuit with the said coils, said means comprising a vibratory element to be actuated by the undulations of a phonographic record groove, a capacity unit inductively in circuit with the oscillating coil of said circuit and in series with the primary of the radio-frequency coil of the circuit, the said unit comprising a fixed element and an element movable with the vibratory element, and an electromagnetic unit including a coil in circuit with the primary of the audio-frequency transformer of the circuit and with the plates of the said tubes of the circuit, said electromagnetic unit including an armature also movable with said vibratory element.

2. In a device of the class described, a vibratory element, means carried thereby for supporting a phonographic stylus, a capacity unit comprising a condenser plate fixedly supported in juxtaposition to the said vibratory element and a companion condenser plate supported in spaced relation thereto by the said vibratory element, and an electromagnetic unit comprising a coil and an armature supported by said vibratory element in the field of the coil.

3. In a device of the class described, a vibratory element, means carried thereby for supporting a phonographic stylus, a capacity unit comprising a condenser plate fixedly supported in juxtaposition to said vibratory element and a companion condenser plate supported in spaced relation thereto by said vibratory element, and an electromagnetic unit comprising a fixed magnet, a coil arranged between the pole pieces of the magnet, and an armature supported by said vibratory element in the field of the coil and between the pole pieces of the magnet.

4. In a device of the class described, a support, a vibratory element, resilient means supporting the vibratory element from the support, means carried by the vibratory element for supporting a phonographic stylus, a fixed condenser plate upon the support, a condenser plate movable with the said vibratory ele-

ment, a fixed magnet upon the support including spaced opposing pole pieces, a coil supported between said pole pieces, and an armature supported by said vibratory element within the field of said coil and between the said pole pieces.

5. In a device of the class described, a support, a vibratory element, resilient means supporting the vibratory element from the support, means carried by the vibratory element for supporting a phonographic stylus, a fixed condenser plate upon the support, a condenser plate movable with the said vibratory element, a fixed magnet upon the support including spaced opposing pole pieces, a coil supported between said pole pieces, an armature supported by said vibratory element within the field of said coil and between the said pole pieces, and means for centering and maintaining the said armature in uniformly spaced relation with respect to the pole pieces and within the field of the coil, comprising a resilient yieldable connection between said support and said element below the point of suspension of the element.

6. In a device of the class described, a support, clamp members, means resiliently supporting the clamp members beneath an extension of said support, a block of rubber interposed between the clamp members, a vibratory element having a head embedded in said block, whereby the member is suspended for vibration and its vibratory movement damped, means carried by the element for the support of a phonographic stylus, a condenser unit comprising a fixed condenser element supported in spaced relation to the vibratory element and a condenser element movable with the said vibratory element, a magnetic unit comprising a fixed magnet having spaced opposing pole pieces, a coil supported between the pole pieces, the said element having a portion extending in centered position within the field of said coil and between the pole pieces, and an armature supported by said portion of said element.

7. In a device of the class described, a support, clamp members, means resiliently supporting the clamp members beneath an extension of said support, means extending between one of said clamping members and said support for effecting adjustment of the clamping members with respect to the support, a block of rubber interposed between the clamp members, a vibratory element having a head embedded in said block, whereby the member is suspended for vibration and its vibratory movement damped, means carried by the element for the support of a phonographic stylus, a condenser unit comprising a fixed condenser element supported in spaced relation to the vibratory element and a condenser element movable with the said vibratory element, a magnetic unit comprising a fixed magnet having spaced oppos-

ing pole pieces, a coil supported between the pole pieces, the said element having a portion extending in centered position within the field of said coil and between the pole pieces, 5 and an armature supported by said portion of said element.

8. In a device of the class described, a support, clamp members, means resiliently supporting the clamp members beneath an extension of said support, means extending between one of said clamping members and said support for effecting adjustment of the clamping members with respect to the support, a block of rubber interposed between the 15 clamp members, a vibratory element having a head embedded in said block, whereby the member is suspended for vibration and its vibratory movement damped, means carried by the element for the support of a 20 phonographic stylus, a condenser unit com-

prising a fixed condenser element supported in spaced relation to the vibratory element and a condenser element movable with the said vibratory element, a magnetic unit comprising a fixed magnet having spaced opposing pole pieces, a coil supported between the pole pieces, the said element having a portion extending in centered position within the field of said coil and between the pole pieces, 25 an armature supported by said portion of said element, and means for yieldably maintaining the said portion of the said vibratory element in position to maintain the armature centrally within the field of the coil and between the pole pieces of the fixed magnet 30 comprising a yieldable resilient connection between said portion of said element and the support.

In testimony whereof I affix my signature.
FLETCHER THORINGTON.
